UNITED STATES PATENT OFFICE.

DOROTHY C. JOYCE, OF PHILADELPHIA, PENNSYLVANIA, ASSIGNOR OF ONE-HALF TO
FRANK D. THOMASON, OF CHICAGO, ILLINOIS.

APPARATUS FOR REMOVING SNOW AND ICE FROM RAILS.

1,101,503.

Specification of Letters Patent. Patented June 23, 1914.

Application filed November 10, 1910, Serial No. 591,633. Renewed December 23, 1912. Serial No. 728,362.

To all whom it may concern:

Be it known that I, DOROTHY C. JOYCE, of Philadelphia, in the county of Philadelphia and State of Pennsylvania, have invented 5 certain new and useful Improvements in an Apparatus for Removing Snow and Ice from Rails, whereof the following is a specification, reference being had to the accompanying drawings.

10 An object of the invention is to provide means for melting the ice and for taking up the water, so as to prevent the refreezing of the same on the rails.

15 A further object of the invention is to provide a device which is movable on the rails with an electrically heated shoe for melting the ice on such rails.

20 These and other objects will in part be obvious, and will in part be hereinafter more fully described.

In the drawings which show by way of illustration one embodiment of the invention, Figure I, is a sectional view more or less diagrammatically showing an apparatus having my improvement applied thereto. Fig. II, is a detail showing the melting shoes in side view. Fig. III, is a longitudinal sectional view through one of the melting shoes. Fig. IV, is a sectional view on the line IV, IV, of Fig. III. Fig. V, is a transverse sectional view on the line V, V, of Fig. III, also showing the upper part of the rail. Fig. VI, is a side view of the shoe for taking up the water. Fig. VII, is a longitudinal sectional view through the shoe for taking up the water. Fig. VIII, is a view on the line VIII, VIII, of Fig. VII, also showing the upper part of the rail. Fig. IX, is a sectional view showing the 40 electrical connection at one end of the melting shoe. Fig. X, is a longitudinal sectional view showing a modified form of shoe for taking up the water.

I have shown my invention as embodied 45 in an organized apparatus which may be propelled along a street railway in the usual manner. Said device consists of a body structure 1, which is mounted on wheels 2, 2. Said device is adapted to be propelled 50 in the usual manner by a motor and by a trolley connection 3.

In order to melt the ice which accumulates on the rails, I have provided my device with melting shoes 4, 4. While I have shown herein two melting shoes, it is obvious that one shoe may be used, or any number of shoes may be used without departing from the spirit of my invention. Said melting shoes are carried by a supporting frame 5. As herein shown, the 60 shoes are connected to the frame by chains 6, and 7. It is obvious, however, that any other flexible connection may be substituted if desired for the chains herein shown. Each chain is connected at one end to a 65 suitable lug on the frame 5, and at the other end to a similar lug on the shoe. The chains are so mounted as to incline toward each other. Any slight obstruction on the rail will, therefore, cause the forward end of the 70 shoes to dip downward and increase the efficiency of contact between the shoe and the rails. The shoes are prevented from lateral movement and held in alignment with the rails by guiding bars 8, and 9, which are 75 supported from the frame 5, by arms 10, 10. These bars allow the shoes to move up and down freely and to a certain extent follow any slight curvature in the rails. The frame 5, is pivoted to one end of a bar 11. 80 The other end of the bar 11, is pivoted to a lug 12, mounted on the body structure of the apparatus. This bar 11, serves to drag the frame and the shoes along the rails. The frame 5, is provided with an eye 13, near 85 each end thereof, and a chain 14, connected at its ends to the eye in the frame, is also connected intermediate its ends to a chain or other flexible member 15. The chain 15, extends over a pulley 16, and is connected 90 to a lever 17. By swinging the lever 17, the frame 5, and the melting shoe supported thereby may at any time be lifted free of the rails, or by swinging the lever in the opposite direction, the shoes may be lowered on 95 to the rail, so that the entire weight of the shoes and frame 5, will be carried by the rail.

In order to heat the shoes, I have provided a generator 18, which may be of any 100 suitable design and said generator, as herein shown, is directly connected with the

motor 19. The motor 19, is connected through the usual switch 20, with the trolley line, and when said switch is closed, the motor may be operated, which will in turn operate the generator. I have shown the usual motor starting rheostat at 21.

The current from the generator 18, passes through the lines 22, and 23, and the cut out 24, to the melting shoe. The wires leading to 10 the melting shoe pass through a suitable insulating sleeve 25, which is held in the usual manner within a screw threaded cap 26. The line 22, is connected at one end to a resistance bar 27, and the opposite end of said 15 resistance bar is connected with the line 23. Said resistance bar is supported by the terminals of the wires 22, and 23, and lies within the hollow melting shoe. Said resistance bar as herein shown, extends in zig zag 20 direction, so as to increase the surface thereof. The shoe is closed by a removable plate 28, which is secured to the body of the shoe by suitable screws, or in any other desired manner. An asbestos pad 29, is secured to 25 the under surface of the plate 28, and being a non-conductor of heat, will tend to throw the heating effect of the resistance bar 27, downward into the portions of the shoe which contact with the rails. A sheet of insulation 30, is placed in the bottom of the pocket in the melting shoe to prevent short circuiting through the shoe proper.

In the operation of my device, the shoes are lowered into contact with the rail by the 35 manipulation of the lever 17, and the switch controlling the motor closed, which will at once start into action the generator. Upon closing the cut out 24, the current from the generator passes through the 40 resistance bars 27, and thus heats the melting shoes which in turn will melt the ice by virtue of their contact with the rails.

In order to prevent the water resulting from the melting of the ice from refreezing 45 as soon as my electrically heated shoe has passed over the rail, I have provided a device for taking up the water from the rails. Said device as shown in Figs. VI, VII, and VIII, is made in form similar to the melting 50 shoe, and consists of a central portion 31, and two pivoted sections 32, and 33. The central section 31, of the shoe is formed with a pocket 34, which is connected by a passage 35, to a flexible tube 36. The sections 55 32, and 33, are also provided with pockets 37, and passages lead to said flexible tube 36. The passages for the sections 32, and 33, pass through the pivot bolts supporting the same.

At the lower face of the shoe for taking 60 up the water, I have formed a rib, which is adapted to run in the groove in the upper face of the rail. Slots are formed in said rib which lead to the pockets 34, and 37. Said glets also extend from one section of the shoe

to the adjacent sections and to the forward 65 end of the shoe, so that when said shoe slides along the rail, a passage is formed underneath, the same to allow the water which accumulates in the groove of the rail to pass underneath the shoe and not be thrown 70 therefrom, as would be the case if the shoe was provided with a solid forward portion.

The shoe for taking up the water is supported by a frame 38, through the chains 39, and 40. Said chains are attached to suitable lugs on the shoe and the frame respectively. Said chains also are inclined outwardly so that said shoe may rise and pass over any slight obstruction on the rail. Side bars 41, 41, are provided for maintaining the shoe 80 which takes up the water in proper alignment with the rail. These side bars are carried by arms 42, rigidly secured to the frame 38. The frame 38, at its forward end is pivoted to a bar 43, which in turn is pivoted 85 to a lug 44, carried by the body structure of the apparatus. This bar 43, serves as a means for dragging the frame 38, and the shoe for taking up the water, along the rails. A chain 45, is connected to the frame 38, near 90 each end thereof, and intermediate its ends is connected to another chain 46. The chain 46, passes over the pulley 47, and is connected with the lever 48. By manipulating the lever 48, the shoe for taking up the 95 water will be raised from the rails, or lowered into contact therewith.

The flexible pipe 36, is connected to a suction pump 49, which is supported by a downwardly projecting arm 50. The shaft 51, of 100 the suction pump 49, is directly connected with a motor 52, which is operated from the trolley, and controlled by a switch 53, which may be of any desired construction. The water lifted by the suction pump from the 105 rail, is forced through a pipe 54, into a reservoir 55, carried by the apparatus.

In Fig. X, I have shown a slightly modified form of shoe for taking up the water from the rail. Said shoe consists of a body 110 section 56, in which is formed a pocket 57, and a curved passage 58, leading from the pocket 57, underneath the same to the front end of the shoe. A pipe 59 extends down into the pocket 57, to a point below the 115 ledge 60. The water lying in the groove in the rail will be forced along the inclined passage and upward into the pocket. The suction pipe 59, extending beneath the 120 surface of the water and connected with the suction pump, will lift the water into the storage tank or reservoir 55.

While I have shown an organized apparatus for melting the snow and taking up the water, it is obvious that my electrically 125 heated shoe for melting the snow or ice may be attached if desired to the ordinary street car in advance of the running wheel, and

the snow or ice in front of the wheels melted. It is also obvious that minor changes in the details of construction may be made without departing from the spirit of my invention.

Having thus described my invention, I claim:—

1. An apparatus for removing ice from rails, including in combination, means for melting the ice, and means for taking up the resulting water from the rails.

2. An apparatus for removing ice from rails including in combination, an electrically heated shoe for melting the ice, and means for taking up the resulting water from the rails.

3. An apparatus for removing ice from rails including in combination, means for melting the ice, and suction means for taking up the resulting water from the rails.

4. An apparatus for removing ice from rails including in combination, an electrically heated shoe for melting the ice, and suction means for taking up the resulting water from the rails.

5. An apparatus for removing ice from rails including in combination, means for melting the ice, and means for taking up the resulting water, including a hollow shoe and suction means connected with such hollow shoe.

6. An apparatus for removing ice from rails including in combination, a storage tank, an electrically heated shoe and means for lifting the resulting water from the rails to said storage tank.

7. An apparatus for removing ice from rails including in combination, an electrically heated shoe, a storage tank, means for taking up the water in the rear of the melting shoe and conveying the same to said storage tank.

8. An ice melter for rails including in combination, a shoe having a rib adapted to engage and follow the groove in the rails,

and means for electrically heating said shoe.

9. An ice melter for rails including in combination, a shoe made in sections, means for flexibly connecting said sections, said sections having a rib adapted to engage the groove in the rail, and means for electrically heating said shoe.

10. An ice melter for rails including in combination, a shoe, an arm supporting said shoe, means for yieldingly pressing said shoe against the rails, said shoe having a rib adapted to engage the groove in the rails, and means for electrically heating said shoe.

11. An ice melter for rails including in combination, a shoe, an arm to which said shoe is pivotally connected, means for yieldingly pressing said arm for holding the shoe in contact with the rails, said shoe comprising sections flexibly connected together, a rib formed on said shoe and engaging grooves in the rails, and means for electrically heating the shoe.

12. An apparatus for removing ice from rails including in combination, a melting shoe, a frame, flexible connection between said frame and said shoe, bars for holding said shoe in alinement with the rails, and means whereby said frame may be raised and lowered.

13. An ice melter for rails including in combination, a hollow shoe having a rib adapted to engage and follow the groove in the rails, a resistance bar located within said shoe, a plate for covering said shoe, a heat absorbing pad located between said plate and said resistance bar, and means for electrically heating said shoe.

In testimony whereof, I have hereunto signed my name at Philadelphia, Pennsylvania, this ninth day of November 1910.

DOROTHY C. JOYCE.
